CLEMENT CIMOROSI, OF ELKTON, MARYLAND, ASSIGNOR TO ALBERTO CIMOROSI, OF ELKTON, MARYLAND.

TORPEDO CASING.

Application filed April 8, 1927. Serial No. 181,939.

My invention relates to torpedo casings and has for its object to provide a casing having certain structural features whereby the ends of the casing are made much stronger than those heretofore produced.

This object, and other advantageous ends which will be described hereinafter, I attain in the following manner, reference being had to the accompanying drawing in which

10 Figure 1 is a fragmentary view, partly in section, of a tube from which my improved torpedo casings are made, and

15 Figure 2 is a view similar to Figure 1 but showing a crimp formed in one end of the tube.

Figure 3 is a central cross sectional view of a completed torpedo, showing the manner in which both of its ends are crimped, and

20 Figure 4 is a perspective view of the torpedo shown in Figure 3.

Referring now more in detail to the drawings, the tube 5 is made in any desired length from a continuous strip of paper which is coated with paraffin and rosin during the 25 winding process. One end of tube 5 is crimped inwardly, then under and outwardly, as shown at 6 in Figure 2, so as to leave a relatively small opening 7 inside the folded edge of the crimp. A casing 8, of any desired length, is cut from the crimped end of tube 5 and a disk 9 inserted against the inner 30 side of crimp 6. Casing 8 is then filled with explosive 10 and a second disk 9 placed on top of the explosive and the end 11 crimped similarly to end 6.

A torpedo casing made in this manner has

flat ends of double thickness, the edges of openings 7 are reinforced by the folding under of the material, and openings 7 are relatively small, consequently the ends of 40 the casing are much stronger than in torpedoes made in any of the usual ways and the torpedo is capable of producing a much louder explosion. Also, disks 9 may be thinner than those usually employed and no 45 gluing or cementing of the ends is necessary.

While I have described my invention as taking a particular form, it will be understood that modifications may be made without departing from the spirit thereof, and 50 hence I do not limit myself to the precise construction set forth, but consider that I am at liberty to make such changes and alterations as fairly come within the scope of the appended claim.

Having thus described my invention, what I claim as new and desire to secure by Letters Patent is:—

55 A torpedo casing consisting of a tube of substantially greater length than the torpedo 60 for which it is designed, the free ends of the tube being bent inwardly at a right angle to the axis of the tube then outwardly with the edge of the outwardly bent portion engaging the interior cylindrical wall of the tube 65 thereby providing a flat top covering substantially the entire area of the end of the tube but leaving a small opening in the center.

In testimony whereof I have signed my name to this specification.

CLEMENT CIMOROSI.
